THERMOELECTRIC DEVICE

William A. Ray, Glendale, Calif.

Application April 5, 1941, Serial No. 387,103

5 Claims. (CL 136—5)

My present invention relates to thermoelectric devices, and particularly to those of the type adapted for the generation of electrical power sufficient to operate a sensitive switching device or pilot valve, in distinction to those of the type employed merely for temperature measurement. Thermoelectric generators of the former type are commonly employed in connection with the control of gaseous fuel consuming furnaces, the hot junction end portion of the device usually being arranged to be heated by the flame of a pilot burner provided for the main burner. The power produced by the pilot-burner-heated thermoelectric device may conveniently be employed for the energization of an electrically operated pilot valve controlling a fuel-pressure-operated main valve for the furnace, an obvious advantage being that the system is then independent of other sources of electrical energy. An additional advantage of this arrangement lies in the fact that, if the pilot burner should accidentally become extinguished, the resultant cessation of current generation by the thermoelectric device effects closure of the furnace valve, thereby rendering the system "safe."

In the prior art, thermoelectric devices of the type indicated have usually been composed of relatively short thermocouple elements, especially when a plurality of pairs of these elements were employed. The reason for the use of short elements is partly on account of the high cost of the materials of which they are generally composed, and also because of the high electrical resistance of these materials which, if the elements were of substantial length, would effect a prohibitive power loss in the system; it being considered that the available power, even when the best thermoelectric materials are employed, is of a very low order—generally not more than about 20 milliwatts being available from a pilot-burner-heated thermoelectric device constructed of materials capable of withstanding the heat of a gas flame.

When the thermoelectric elements are relatively short, after their hot junction end portions have been heated for a short space of time, their cold junction ends also become heated; the temperature differential between the hot and cold junctions thus being reduced, the thermoelectric generation is correspondingly reduced. In a typical furnace installation, undesirable heating of the cold junctions is generally due mainly to conduction of heat from the hot junctions, increase of ambient temperature and radiation from the main burner also contributing to a minor degree.

to the heating of the cold junctions. It is therefore an object of my invention to provide a thermoelectric device constructed of relatively short elements, which elements are so composed that the thermoelectric generation is relatively constant regardless of the heat gradient along the elements.

Another object is to provide, in a thermoelectric device of the type described, thermocouple elements, different portions of which are of materials having dissimilar thermoelectric powers or positions on a thermoelectric scale wherein the E. M. F. of the various materials is plotted against temperature. Such a scale is graphically illustrated on page 307 of "Pyrometric Practice," U. S. Bureau of Standards Technologic Paper No. 170, all the commercial alloys hereinafter referred to being included in that scale, which is therefore reproduced in part in the accompanying drawing.

In my copending application Serial No. 377,274, filed February 4, 1941, I have disclosed a thermocouple adapted to be heated by the flame of a pilot burner for a furnace main burner, wherein one of the thermoelectric elements is of such length that it may be extended to a region outside the furnace; this element is preferably of an alloy such as Copel or constantan, the electrical resistance of which is not excessive. The other element is relatively short, a wire of good heat conducting material, such as copper, being provided for the extension of this element to the exterior of the furnace. The short element referred to is preferably of an alloy such as Chromel or nichrome which, while having relatively high thermoelectric power, also has high electrical resistance. For this reason, increased generation is effected by the provision of the copper extension, as that metal has somewhat similar thermoelectric properties to that of Chromel or nichrome and is approximately 50 times as conductive, both electrically and thermally. However, it has been found that the generation of such a thermocouple is reduced after prolonged heating, on account of the rise in temperature at the junction between the short element and the copper extension. The reason for this reduction is apparent when one considers that, if the temperature of the junction between the copper extension and the short element were to rise to the same temperature as that of the original hot junction (between the Copel and Chromel elements), the effective hot junction would then be that between the copper and the elongated Copel element (as the short Chromel element, being at the same temperature

throughout its length, would have no thermoelectric effect) and the generation would therefore be reduced on account of the lower thermoelectric power of the copper. However, in practice, such an extreme condition is impossible on account of the high thermal conductivity of the copper which constantly conducts heat away from its junction with the short element. It is therefore another object of my invention to provide means for so compensating such a thermocouple that its generation is substantially constant.

Other objects and advantages of my invention will be found in the description, the drawing, and the appended claims.

For complete understanding of the invention, reference may be had to the following detailed description and accompanying drawing, wherein:

Figure 1 is a diagrammatic view of a thermoelectric device embodying my invention;

Figure 2 is a diagrammatic view of a modified form of thermoelectric device also embodying my invention; and

Figure 3 is a graph (referred to above) indicating the thermoelectric power of various alloys and elements.

Referring first to Fig. 1 of the drawing, the numerals 11 and 12 generally indicate a pair of thermocouple members; the upper and lower portions 13 and 14, respectively, of member 11 being of different materials, and the whole portion 15 of member 12 being of a still different material. Each pair of members is joined at its upper end to form a "hot" junction 16, and the series of pairs of members are connected in electrical series at their lower ends to form "cold" junctions 17. The thermopile thus formed is connected by copper leads 18 to a suitable load indicated by a resistance element 19. The members are preferably in the form of wires or strips of metals capable of withstanding the heat of an ordinary gas flame, the various portions and leads being united by fusion or welding. A typical thermopile structure is disclosed in U. S. Patent No. 2,236,609, granted April 1, 1941 to W. R. Ray.

The portion 15 is preferably of an alloy such as Chromel or nichrome which has a relatively high positive power (with respect to platinum) as is indicated in the graph of Fig. 3. The upper portion 13 of member 11 is preferably of an alloy such as Alumel which occupies a negative position on the thermoelectric power scale, and the lower portion 14 of this member is preferably of an alloy such as Copel or constantan which is also negative but to a higher degree than Alumel.

In the prior art, the members 11 and 12 were usually wholly of alloys such as Copel and Chromel, respectively, with the result that after the hot junction had been heated for a short space of time the cold junctions also became somewhat heated due to thermal conduction through the members, and the thermoelectric generation was accordingly reduced. With prolonged heating the reduction of available power might be quite serious.

In the thermocouple of my present invention (considering first a single pair of the members of Fig. 1) upon initial heating of junction 16, the remainder of the elements being substantially cold, the generation will be that due solely to the heating of the junction between the Chromel portion 15 and the Alumel portion 13; the lower Copel portion 14 now having no thermoelectric effect upon the generation as the intermediate junction 16' between it and the upper Alumel

portion 13 is cold. The E. M. F. at the particular temperature difference between the hot and cold junctions can thus be determined by measuring on the graph the distance between the Chromel and Alumel lines at that temperature. When by continued heating the lower portions of the elements also become heated, the temperature difference between the hot junction 16 and the cold junction (which is effectively at the lower ends of members 14 and 15) is decreased. However, the generation is not correspondingly reduced as the temperature of the intermediate junction 16' between the Copel portion 14 and the Alumel portion 13 (being nearer to the source of heat) has obviously been increased to a greater degree than that of the cold junction, with the result that the Copel (which has negative thermoelectric power higher than that of Alumel) becomes effective to influence the generation.

The reason for the compensating effect produced by the Copel portion will be best understood by assuming an extreme condition wherein the intermediate junction 16' between members 13 and 14 is at the same temperature as the hot junction 16. When such is the case, the Alumel portion 13 has no effect on the generation as it is at the same temperature throughout its length, and the thermoelectric power can be determined by the distance between the Copel and Chromel lines at the particular temperature difference between the hot and cold junctions, it being noted that the generation of a Copel-Chromel combination is the highest indicated on the graph. However, under the extreme heating conditions assumed, the cold junction also becomes considerably hotter, the net result being a balance between the gain at the hot junction and the loss at the cold junction. It will thus be seen that, in the construction shown in Fig. 1, there is a constant balance of the thermoelectric generation regardless of the temperature difference between the hot and cold junctions when heat is continuously applied to the hot junction. This improvement results from the provision of material for the lower portion 14 of member 11 which has a higher thermoelectric power with respect to that of member 12 than that of the material of the upper portion 13; the relative lengths of members 13 and 14 depending mainly on how much of the portion 13 adjacent the hot junction 16 is subjected to the flame. Obviously, the same general result may be produced by choosing materials from other parts of the thermoelectric scale in the same relative order; or by reversing their order on the scale, as, for example, by making member 12 of Copel, portion 13 of Alumel, and portion 14 of Chromel. However, the general arrangement described above is preferred, particularly for the reason that the alloys Alumel and Chromel can better withstand the effect of high temperatures (without excessive corrosion or oxidization) than the alloy Copel. Also, obviously, materials other than those shown in the graph of Fig. 3 may be employed, especially when the thermocouple is to be heated to temperatures lower than that produced by a gas flame, or when "cold" (instead of heat) is employed for producing the necessary temperature differential, as in connection with a refrigeration system. It is to be understood that the terms "hot junction" and "cold junction" are interchangeable under some conditions and are employed herein to conveniently indicate relative different temperature of the junctions.

Set forth below are examples of conditions under which constant E. M. F. is produced by a single thermocouple of the thermopile shown in Fig. 1 at progressively varying temperatures of the intermediate and cold junction—it being assumed that the hot junction temperature remains the same. The E. M. F. of the thermocouple is calculated by adding, algebraically, the E. M. F.'s generated at each of its junctions at the given temperatures, as indicated in the graph of Fig. 3. In this method of calculation, the relations of the elements at each of the junctions are set down in sequence around the circuit—conveniently, in this particular instance, in a counterclockwise direction in order to obtain a result having a plus value. The copper member 18 has not been included because the interposition of an additional element when both ends are at the same temperature does not affect the voltage of the circuit. It will be understood that, while the exactly-equal results shown by these examples are theoretical, in practice the results are substantially the same over a considerable range of temperature with proper proportioning of the three elements to meet the particular condition under which heat is applied to the hot junction.

Example 1

	Millivolts
Junction 16: Chromel-Alumel at 500° C	+21.0
Junction 16': Alumel-Copel at 20° C	+0.3
Junction 17: Copel-Chromel at 20° C	-1.3
	+20.0

Example 2

	Millivolts
Junction 16: Chromel-Alumel at 500° C	+21.0
Junction 16': Alumel-Copel at 75° C	+2.0
Junction 17: Copel-Chromel at 45° C	-3.0
	+20.0

Example 3

	Millivolts
Junction 16: Chromel-Alumel at 500° C	+21.0
Junction 16': Alumel-Copel at 150° C	+4.5
Junction 17: Copel-Chromel at 80° C	-5.5
	+20.0

Example 4

	Millivolts
Junction 16: Chromel-Alumel at 500° C	+21.0
Junction 16': Alumel-Copel at 220° C	+7.0
Junction 17: Copel-Chromel at 120° C	-8.0
	+20.0

While the intermediate junction 16' is shown in the drawing as being relatively near the hot junction 16, it does not attain a very high temperature on account of the relatively low thermal conductivity of the Alumel portion; preferably, 60 by the hot-junction extremity of this portion being subjected to heat.

Comparing the results obtained in the above examples with those which would be obtained under the same conditions of temperature differential with a thermocouple constructed of only Chromel and Alumel, we find the following E. M. F. values:

Example 1a

	Millivolts
Junction: Chromel-Alumel at 500° C	+21.0
Junction: Alumel-Chromel at 20° C	-1.0
	+20.0

Example 2a

	Millivolts
Hot Junction: Chromel-Alumel at 500° C	+21.0
Cold Junction: Alumel-Chromel at 45° C	-2.0
	+19.0

Example 3a

	Millivolts
Hot Junction: Chromel-Alumel at 500° C	+21.0
Cold Junction: Alumel-Chromel at 80° C	-3.0
	+18.0

Example 4a

	Millivolts
15 Hot Junction: Chromel-Alumel at 500° C	+21.0
Cold Junction: Alumel-Chromel at 120° C	-4.5
	+16.5

The function of the thermopile shown in Fig. 20 1 is similar to that of the single pair of members discussed above, the advantage of the compensating arrangement of my invention being even greater when it is applied to a thermopile because of the isolation of the intermediate cold junctions 17. In a single thermocouple having connecting leads of copper, the cold junction does not rise to as high a temperature as that of the isolated intermediate cold junctions of a thermopile due to the conduction of heat from the cold junction by the leads. In the patented thermopile structure referred to above, the members are conveniently about two inches long.

Referring now to Fig. 2 of the drawing, the various elements corresponding to the elements of Fig. 1 have been assigned numerals which are greater by 10 than those in Fig. 1; the short upper end portion 23 of member 21 preferably being of an alloy such as Alumel, the long lower end portion 24 of Copel or constantan, and the short upper portion 25 of member 22 of Chromel or nichrome. The main difference between the thermocouple members of Fig. 2 and those of Fig. 1 resides in the greater relative length of the members 21 and 22 and also in the provision of a long copper portion 28 for the extension of the short Chromel portion 25. As compared with the two inch convenient length of members 11 and 12 stated above, the members 21 and 22 may be one or two feet in length and connected directly to the device to be operated, indicated by resistance element 29. As has been mentioned hereinabove the resistance of Chromel or nichrome is very high, that of copper is very low, and the thermoelectric property of copper is somewhat similar to that of nichrome and Chromel, as is indicated in the graph of Fig. 3. For this reason, it has been found that the electrical power delivered to the load is increased when copper is substituted for a substantial lower portion of a Chromel or nichrome thermocouple element. Upon prolonged heating of the hot junction 26, the temperature at the intermediate junction 26'' between the Chromel portion 25 and the copper portion 28 rises, with resultant decrease in thermoelectric generation. However, this decrease is offset by the increased generation due to the corresponding rise in temperature at the intermediate junction 26' between the Alumel portion 23 and the Copel portion 24, as has been described above in connection with Fig. 1. The total thermoelectric generation thus remains constant. The relative lengths of the various portions of the members 70 65 55 45 35 25 15 may be arranged to suit the particular condi-

tions to which the thermocouple is subjected, such as the position of the flame with respect to the thermocouple, ambient temperature near the upper end of the thermocouple, and that at the load. As an example, the portion 23 is shown as being shorter than the portion 25.

It is to be understood that modifications other than those mentioned hereinabove may be made without departing from the spirit of my invention and I intend therefore to be limited only by the scope of the appended claims.

I claim as my invention:

1. A thermocouple adapted to generate substantially constant voltage and comprising a pair of elongated members joined at one of their respective ends to form a "hot" junction, the opposite ends of the members forming effectively a "cold junction," said members being so short that said cold junction is substantially affected by the temperature of said hot junction, one of said members being wholly of metal having one thermoelectric power, the other of the members being composed of two sections joined longitudinally to form an intermediate junction, the first section between the hot junction and the intermediate junction being of metal having a thermoelectric power differing from that of the first-mentioned member, the other section between the intermediate junction and the cold junction being of metal having a thermoelectric power also differing from that of the first-mentioned member and in the same sense as that of said first section but to a greater degree.

2. A thermocouple adapted to generate substantially constant voltage and comprising a pair of elongated members joined at one of their respective ends to form a "hot" junction, the opposite ends of the members forming effectively a "cold junction," said members being so short that the temperature of said cold junction is increased substantially upon prolonged heating of said hot junction, one of said members being wholly of metal having one thermoelectric power, the other of the members being composed of two sections joined longitudinally to form an intermediate junction, the first section between the hot junction and the intermediate junction being of metal having a thermoelectric power differing from that of the first-mentioned member, said first section being of such length that said intermediate junction attains a temperature intermediate that of said hot and cold junctions upon prolonged heating of said hot junction, the other section between the intermediate junction and the cold junction being of metal having a thermoelectric power also differing from that of the first-mentioned member and in the same sense as that of said first section but to a greater degree.

3. A thermocouple adapted to generate substantially constant voltage and comprising a pair of elongated members joined at one of their respective ends to form a "hot" junction, the opposite ends of the members forming effectively a "cold junction," said members being so short that the temperature of said cold junction is increased substantially upon prolonged heating of said hot

junction, one of said members being wholly of metal chosen from the group consisting of Chromel and nichrome, the other of the members being composed of two sections joined longitudinally to form an intermediate junction, the first section between the hot junction and the intermediate junction being of Alumel, said first section being of such length that said intermediate junction attains a temperature intermediate that of said hot and cold junctions upon prolonged heating of said hot junction, the other section between the intermediate junction and the cold junction being of metal chosen from the group consisting of Copel and constantan.

4. In a thermoelectric device for the generation of substantially constant voltage: a plurality of thermocouples each comprising a pair of elongated members and joined in electrical series to form a thermopile having a series of "hot" and of "cold" junctions, said members being so short that the temperature of said cold junctions is increased substantially upon prolonged heating of said hot junctions, one member of each of said pairs being wholly of metal having one thermoelectric power, the other member of each pair being composed of two sections joined longitudinally to form an intermediate junction, the first section of each of said other members between the hot junction and the intermediate junction being of metal having a thermoelectric power differing from that of the first-mentioned member, said first section being of such length that said intermediate junction attains a temperature intermediate that of said hot and cold junctions upon prolonged heating of said hot junction, the other section of each of said other members between the intermediate junction and the cold junction being of metal having a thermoelectric power also differing from that of the first-mentioned member and in the same sense as that of said first section but to a greater degree.

5. In a thermoelectric device for the generation of substantially constant voltage: a plurality of thermocouples each comprising a pair of elongated members and joined in electrical series to form a thermopile having a series of "hot" and of "cold" junctions, said members being so short that the temperature of said cold junctions is increased substantially upon prolonged heating of said hot junctions, one member of each of said pairs being wholly of metal chosen from the group consisting of Chromel and nichrome, the other member of each pair being composed of two sections joined longitudinally to form an intermediate junction, the first section of each of said other members between the hot junction and the intermediate junction being of Alumel, said first section being of such length that said intermediate junction attains a temperature intermediate that of said hot and cold junctions upon prolonged heating of said hot junction, the other section of each of said other members between the intermediate junction and the cold junction being of metal chosen from the group consisting of Copel and constantan.

WILLIAM A. RAY.
